UNITED STATES PATENT OFFICE.

CHRISTEN STEENSGAARD, OF ASTORIA, NEW YORK.

CLOTHES-LINE SUPPORT.

1,200,773.

Specification of Letters Patent. Patented Oct. 10, 1916.

Application filed May 14, 1915. Serial No. 28,079.

To all whom it may concern:

Be it known that I, CHRISTEN STEENSGAARD, a citizen of the United States, residing at Astoria, Long Island, in the county 5 of Queens, State of New York, have invented certain new and useful Improvements in Clothes-Line Supports; and I do hereby declare the following to be a full, clear, and exact description of the invention, such as 10 will enable others skilled in the art to which it appertains to make and use the same.

This invention relates to clothes line supports.

The object of the invention resides in the 15 provision of a clothes line support adapted to be attached to a window frame and which can be swung through the window into the building when loading and unloading the line so as to avoid the danger of leaning out 20 of the window when it is desired to apply the clothes to or remove same from the line.

A further object of the invention resides 25 in the provision of a clothes line support adapted to be swung to a position exteriorly of the building and when so disposed will not interfere with the raising and lowering of the window sash.

With the above and other objects in view the invention consists in the details of construction and in the arrangement and combination of parts to be hereinafter more 30 fully described and particularly pointed out in the appended claims.

In describing the invention in detail reference will be had to the accompanying 35 drawings wherein like characters of reference denote corresponding parts in the several views and in which—

Figure 1 is a vertical section through a 40 window showing the improved support applied and positioned in the interior of the building; Fig. 2, a view similar to Fig. 1 with the support swung to a position on the exterior of the building; Fig. 3, a plan 45 view of what is shown in Fig. 2; Fig. 4, an enlarged section on the line 4-4 of Fig. 2; Fig. 5, a section on the line 5-5 of Fig. 2, and Fig. 6, a perspective view of the bracket arm employed in the support.

Referring to the drawings 50 indicates a window frame mounted in the usual manner in the wall 11.

The improved clothes line support comprises a bracket arm 12 detachably secured 55 to one of the sides of the frame 10 through the medium of screws 13. The free end of

the bracket 12 terminates in a circular portion 13' provided with a central opening 14 and having formed on its upper and lower sides radially extending teeth 15 arranged 60 concentrically around the opening 14. Rotatably engaged upon the circular portion 13' is a head 16 the base of which is provided with radial teeth 17 coöperating with the adjacent teeth 15 of the circular portion 65 13'. Engaged through the opening 14 is a threaded stem 19. Formed in the head 16 is an eye 21 for a purpose that will presently appear. Threaded on the lower end of the stem 19 is a clamping nut 22 which 70 when screwed home engages the inner wall of a recess 20 in the lower side of the portion 13' and clamps the head 16 firmly to the bracket arm with the teeth 17 interlocking with the teeth 15 and securing the 75 head against rotation. Formed integral with the head 16 and extending laterally therefrom is an arm 23 the free end of which terminates in a rectangular frame portion 24 and journaled in this frame portion 80 is a pulley 25.

The clothes line is indicated at 26 and is of the endless type. In applying the line same is trained through the eye 21, then over the pulley 25 and back around the 85 clamping nut 22. When it is desired to swing the arm 23 to the interior of the building it is only necessary to loosen the nut 22 sufficiently to permit the cap 16 to be raised 90 far enough to disengage the teeth 17 from the teeth 15.

It will be noted that the parts of the support are so formed and arranged that they can be assembled on either side of a window without interfering with the successful operation of the support. To change the support from one side of a window frame to the other it is only necessary to reverse the bracket arm 12 and then assemble the remaining portions in the manner disclosed. 95 100

What is claimed is:—

A clothes line support comprising a bracket arm adapted to be secured at one end to a window frame, a circular portion formed on the other end of said arm and 105 having a central opening, radial teeth formed on both sides of said circular portion about said opening, and both sides of said circular portion being recessed centrally about the opening, a head engaged 110 over the upper side of the circular portion and having radial teeth on its base adapted

to coöperate with the radial teeth on the circular portion, a depending stem carried by the head and extending through the opening in the circular portion, a nut threaded on the lower end of the stem and adapted to engage the inner wall of the recess in the lower side of the circular portion to clamp the head against rotation, a lateral arm formed integral with the head and

adapted to swing in a horizontal plane, and a pulley journaled on the free end of said arm.

In testimony whereof, I affix my signature, in the presence of two witnesses.

CHRISTEN STEENSGAARD.
